UNITED STATES PATENT OFFICE.

GEORGE H. PALLADY, OF REDONDO BEACH, CALIFORNIA.

LIFE-PRESERVER.

1,385,581.

Specification of Letters Patent. Patented July 26, 1921.

Application filed December 2, 1920. Serial No. 427,383.

To all whom it may concern:

Be it known that I, GEORGE H. PALLADY, a citizen of the United States, residing at Redondo Beach, in the county of Los Angeles and State of California, have invented certain new and useful Improvements in Life-Preservers; and I do declare the following to be a full, clear, and exact description of the invention, such as will enable others skilled in the art to which it appertains to make and use the same.

This invention relates generally to life preservers, and particularly to that type of life preservers which are designed to be worn around the neck of a person. Hence, the invention may be properly called a life collar.

One object of the invention is to provide a life preserver which is permanently filled with air so that it is at all times ready for use.

Another object of the invention is to provide a collar type life preserver provided with means whereby it may be quickly and easily fastened around the neck of a person, or removed therefrom.

A further object of the invention is to provide a life preserver in which the air is contained in a plurality of independent containers inclosed one within the other so that if the inner container becomes punctured for some reason or the other, the container surrounding it will prevent the air from the inner container from escaping and will prevent the life saver as a whole from becoming inoperative.

A still further object of the invention is to generally improve upon devices of this class by the provision of a comparatively simple, strong, durable and inexpensive construction, one which will be efficient and reliable in operation, and well adapted to the purpose for which it is designed.

With the above and other objects in view, the invention consists of various details of construction, and the combination and arrangement of parts as are hereinafter fully described and claimed.

The descriptive matter of the specification is supplemented by the accompanying drawing in which similar reference characters are used to designate like parts throughout the several views, and in which:

Figure 1 is a perspective view of a device constructed in accordance with this inven-

tion, said view illustrating the manner in which the device is worn; and

Fig. 2 is an enlarged horizontal sectional view of the device.

In the drawing, the numerals 1 and 2 designate a pair of longitudinally curved or arcuate metal tubes, which, after having been filled with air, are sealed tight so as to prevent the escape of the air. The tubes 1 and 2 are of such curvature, that when 60 they are disposed side by side in the manner shown in Fig. 2 of the drawing, the structure formed will be substantially U-shape. Placed around the tubes 1 and 2 is a body 3 of packing, which may consist of excelsior 70 or any other suitable material. This body 3 of excelsior may be maintained in place in any suitable manner, such as for instance, by means of a covering 4. A considerable mass of the packing 3 is disposed between 75 the adjacent or abutting ends of the tubes 1 and 2 so as to prevent movement of the cylinders 1 and 2 and of the packing 3 within the covering 4.

The covering 4 and the inclosed body 3 80 of packing, and the cylinders 1 and 2 are substantially U-shaped, and surrounding this is a tube 5 of flexible material, such as rubber. This tube 5 is U-shaped, and is slightly larger in diameter than the diameter of the covering 4. The ends of the tube 5 project beyond the ends of the covering 4, and one of these ends is provided with an inflating valve 6. By means of a suitable pump, the tube 5 may be filled 85 through the inflating valve 6.

Surrounding the tube 5 and conforming closely to the shape of the same is a covering 7 of fabric or other suitable material which will not permit water or air to pass 95 therethrough. The ends of said U-shaped tubular covering 7 are sealed shut so that the entire covering is water-tight and also air-tight.

Secured to the outer side of the covering 7 100 at the ends thereof are straps 8 and 9 provided respectively with coöperating separable fastening devices 10 and 11.

The device is designed to be worn around the neck of a person, and in Fig. 1 of the 105 drawing it is shown in the manner in which it is worn. The flexibility of the mass of packing 3 between the adjacent ends of the tubes or cylinders 1 and 2 permits the device to be opened or spread at its opposite 110

side when it is placed upon the neck of a person, or removed therefrom. After the device is put in place, the fastening devices 10 and 11 are snapped together, and since 5 the device is of such size that it snugly fits around the neck of the wearer, it will retain this position.

The amount of air contained in the tubes or cylinders 1 and 2 is sufficient of itself to 10 float the body of a person, and additional protection is afforded by the volume of air contained in the flexible rubber tube 5. It is preferable to inflate this tube 5 with air by means of an air pump, so that the air contained therein will be under pressure in order that the tube 5 will not be collapsed when submerged in water.

By having the tubes or cylinders 1 and 2 filled with air and sealed tight, and disposed in the flexible rubber tube 5 which is also filled with air, should one or both of the tubes 1 and 2 become punctured, the tube 5 will prevent the air from escaping, and thus the life preserver as a whole will not 25 be rendered inoperative.

The device is made comfortable to the wearer by means of the padding 3 which is placed around the tubes 1 and 2.

From the foregoing description, taken in 30 connection with the accompanying drawing, the construction, use, and advantages of the invention will be readily understood without a more extended explanation.

Various changes in form, proportion, and 35 in the minor details of construction, may be resorted to without departing from the spirit and principle of the invention, as defined in the appended claims.

I claim:

40 1. A device of the class described comprising a sealed air container constituting a sustaining element, a tube inclosing said container, said tube being inflated with air independently of said container, and a water-

45 proof covering surrounding said tube.

2. A device of the class described comprising a pair of sealed air containers constituting sustaining elements for floating a person's body, a tube inclosing said contain-

ers, said tube being inflated with air independently of said containers, and a water-proof covering surrounding said tube.

3. A device of the class described comprising a pair of curved rigid air containers constituting sustaining elements, a U-shaped tube surrounding said containers, said tube being inflated with air independently of said containers, and a U-shaped covering surrounding said tube.

4. A device of the class described comprising a pair of curved rigid air containers constituting sustaining elements, padding of soft material surrounding said containers, a U-shaped tube inclosing said containers, said tube being inflated with air independently of said containers, and a U-shaped covering surrounding said tube.

5. A device of the class described comprising a pair of curved rigid air containers arranged side by side with their inner ends disposed adjacent each other, padding surrounding said containers, a considerable mass of said padding being disposed between the adjacent ends of said containers, a U-shaped tube inclosing said containers and said padding, said tube being inflated with air independently of said containers, a U-shaped covering surrounding said tube, and separable means for fastening the ends of said covering together, the mass of padding between the adjacent ends of said containers permitting the opposite side portions of the device to be spread while being placed upon or removed from a person's neck.

6. A device of the class described including a sealed air-tight tube constituting a sustaining element and inclosed in a larger sealed air-tight inflated tube, and a snap-fastener to secure the device around the neck of the user.

In testimony whereof I have hereunto set my hand in the presence of two subscribing witnesses.

GEORGE H. PALLADY.
